FUSE ORGANIZATION

Ralph W. E. Moore, Pittsburgh, Pa., assignor to
 National Electric Products Corporation, Pittsburgh, Pa., a corporation of Delaware

Application June 4, 1935, Serial No. 24,803

6 Claims. (Cl. 200—119)

This invention relates to fuse organizations of the general type used to protect the individual circuits in residences and other buildings.

Lighting circuits in residences are customarily protected with the well-known plug fuses that are screwed into receptacles or sockets so connected that the current passing to the circuit must flow through the fuse. These fuses are accessible to all sorts of unskilled and ill-advised 10 people; and it is now well-known that the circuits are frequently deprived of the necessary protection by the insertion of fuses of too high rating or by the insertion of tin foil, coins, etc., behind a blownout fuse. Accordingly, various 15 fuse organizations have heretofore been devised for the purpose of preventing over-fusing and increasing the difficulty encountered by the uninitiated in attempting to complete the circuit by foreign objects inserted into the fuse 20 socket.

It is generally recognized that it is not commercially feasible to provide a fuse organization which would render it completely impossible for a skilled electrician to circumvent the fusing of 25 the circuit. However, it is desirable so far as possible to make it very difficult for the uninitiated to circumvent the fusing; and particularly it is desirable to so construct the fuse organization 30 that it cannot be thwarted with articles or materials which the uninitiated have readily at hand.

The present invention is an improvement upon the prior art fuse organizations of the type discussed, and particularly it is an improvement 35 upon the fuse organization disclosed in my prior Patent 1,990,953, issued February 12, 1935.

The general object of the invention is to provide a fuse organization of the general type disclosed in my prior patent which is even more 40 difficult for the uninitiated to circumvent.

A specific object of the invention is to so improve the fuse organization that when made with commercial manufacturing tolerances, it cannot be circumvented to a dangerous degree by the 45 insertion of finely stranded wire, which is one of the things that the uninitiated have readily at hand.

Fig. 1 is an enlarged longitudinal section of a 50 fuse plug of the present organization;

Fig. 2 is a cross section taken on the line 2—2 of Fig. 1;

Fig. 3 is an enlarged longitudinal section of a 55 receptacle for receiving the fuse plug of Fig. 1;

Fig. 4 is a bottom plan view of the receptacle shown in Fig. 3;

Fig. 5 is a top plan view of the receptacle shown in Fig. 3, drawn to smaller scale;

Fig. 6 is a bottom plan view of the exterior cap member of the fuse plug shown in Fig. 1, also on a reduced scale;

Fig. 7 is a detailed view in longitudinal section taken on the line 7—7 of Fig. 2;

Fig. 8 is a detail elevational view, looking from the line 8—8 in Fig. 1.

The fuse plug is built about an interior piece 10 of molded insulating material designated as a whole by 10. This element 10 is molded in one piece and comprises an upper cylindrical wall 11, a depending cylindrical skirt 12, and a partition member 14 from which there depends a perforated boss 13. Telescoped over the member 10 is a threaded sheet metal ferrule 15; and the upper part of the ferrule is provided with an in-turned annular portion 15' (see Fig. 8) that lies against an annular ledge 16 on the exterior 15 of member 10. The ferrule 15 is locked against rotation by lug 16a which projects upwardly from ledge 16 and extends through a cut away space in the inturned portion 15' of the ferrule. A disc 17 of transparent material, such as glass 20 or mica, is positioned on top of the upper cylindrical wall 11; and an outer cap member 18 of molded insulating material is telescoped over the cylindrical wall 11. The outer cap 18 may make a tight frictional fit with wall 11, and additionally these parts may be cemented together. To 25 aid the cement in adhering to the parts, the cemented surfaces may be roughened, as by fine ridges or grooves too small to illustrate.

A center contact button 20 has a head which 30 is co-extensive with the boss 13 and a shank which extends through the aperture in the boss 13. The shank initially terminates in a cup like portion similar to the end of a tubular rivet, but is stamped over to form a flange 22 which secures 35 the button 20 in place in the boss. Preferably, the face of the molded insulating material against which flange 22 is stamped, is formed with four radial channels 24 (Fig. 2) so that the metal of flange 22 extends down into these 40 channels and fixes the head 20 against rotation 45 relative to the boss 13. A fuse link 25 extends from contact button 20, through opening 26, down channel 27 (formed on the interior of cap 18) to ferrule 15. The fuse link is suitably connected to head 20 as by solder at 28 and is also 50 suitably connected to ferrule 15 as by solder at 29.

Venting for the fuse is provided in two ways. 55 Adjacent to the shank of contact button 20, there

are four vertical grooves 39 (Figs. 2 and 7) formed in the material of the partition 14, and each of these vertical grooves 39 terminates in a horizontal groove 31 which extends radially adjacent the upper surface of the head of button 20. Thus gases generated by blowing of the fuse may escape via channels 30 and 31. At the top of wall 11, there are four apertures 26 and gases may escape through these, pass upwardly through grooves 27 to annular groove 33, and radially inward through grooves 34 to the free space immediately above the disc 17. Similarly, gases after passing through apertures 26 may pass downwardly through grooves 27 and out to the air adjacent the upper edge of ferrule 15.

Referring to Figs. 3, 4, and 5, the fuse receptacle is built up about a molded piece of insulated material 50, which has a depending boss 51. The upper portion of the molded piece is provided with a cylindrical recess 52, and the depending boss is provided with a non-circular recess 53. A circuit breaker is formed by a metal plug 54, biased upwardly by spring 55, and provided with a head 56 which closely fits the recess 52. The lower end of plug 54 extends into recess 53 and is there riveted to a washer 57 which is so shaped as to be non-rotatively confined by the non-circular recess 53.

A sheet metal socket 58 has an inturned flange 59; and piece 50 is telescoped into the socket and against the flange. These parts may be held in assembled relation in any suitable way, as by fingers 60 which project into recesses 58a, these fingers being struck from the metal of the socket 35 after piece 50 has been telescoped into the socket.

The socket construction shown in Fig. 3 may be incorporated in a cut-out base after the manner shown in my Patent 1,990,953, or it may be used as an adapter in a standard cut-out base after the manner shown in Schmidt Patent 1,863,383. In either case the fuse of Fig. 1 is screwed into the socket of Fig. 3 and part 50 acts as a fuse selector which rejects fuses of too high rating as explained in my Patent 1,990,953. With a fuse of permissible rating, metal contact button 20 engages head 56 to advance the circuit breaker and close the circuit.

As the fuse is being screwed in, button 20 rotates with the fuse and head 56 cannot rotate (due to washer 57). The contacting surfaces of button 20 and head 56 are cross hatched with fine grooves as shown in Figs. 1, 3, 5, and 7; and thus foreign material inserted in an attempt to bridge the circuit is caught in the grooves of the contacting faces and thereby shredded, broken, and torn. The interior of fuse skirt 12 is grooved with fine grooves 64 and the outer wall of socket piece 50 is correspondingly grooved at 65. The skirt 12 clears the part 50 by only the necessary manufacturing tolerance; and inserted foreign material is also caught and shredded and broken by grooves 64 and 65. The various grooves to catch foreign material are particularly effective against inserted pieces of stranded wire. It should also be noted that the head of contact button 20 is coextensive with boss 13 and enters recess 52 with only the necessary manufacturing tolerance, thereby still further safeguarding against bridging by foreign material.

While various prior art constructions can be made quite effective to forestall bridging if the

parts be made to interfit accurately, it has been found that bridging can still be effected when variations in fit have been allowed sufficient to permit of production on a commercial scale at desirably low costs. With the present invention, however, dangerous bridging by inserted foreign material is exceedingly difficult, if not impossible, even when the device is made with the tolerances necessary for low cost commercial production.

I claim:

1. A fuse organization comprising: a socket for a plug fuse; a fuse selector mounted in the socket; a circuit breaker incorporated in the fuse selector, the circuit breaker having an exposed conducting face engageable by an inserted fuse to move the circuit breaker from open to closed position; and a plug fuse having an exposed conducting face to engage the exposed face of the circuit breaker and rotate relative thereto; the cooperating faces of the fuse and circuit breaker being roughened to exert abrading action on foreign objects inserted into the socket in advance of the fuse.

2. A fuse organization comprising: a socket for a plug fuse, a fuse selector mounted in the socket, and a plug fuse for insertion into the socket, the selector and plug fuse having telescopically related surfaces of insulating material which are roughened to exert an abrading action on inserted foreign objects.

3. In a fuse organization of fuse socket and plug fuse therefor, the socket having a fuse selector in telescopic relation with the fuse and also having a circuit breaker engaged and actuated by the fuse: the improvement which comprises roughened engaging faces on the fuse and circuit breaker and roughened telescopically related surfaces of insulating material on the fuse and selector, for the purpose of exerting an abrading action on foreign objects inserted into the socket in advance of the fuse.

4. A fuse organization comprising: a socket for a plug fuse; a fuse selector mounted in the socket, the fuse selector having cylindrical cavity and flat topped circuit breaker means reciprocably and non-rotatably mounted in said cavity, the top portion of the circuit breaker means making a close fit with the cavity; and a plug fuse having a contact button to engage and depress said circuit breaker means, the contact button also making a close fit with said cavity and the engaging surfaces of the contact button and circuit breaker means being roughened to exert a tearing action on foreign objects inserted in the socket in advance of the fuse.

5. A plug fuse having a projecting boss of insulating material and a metal contact button mounted on said boss and secured against rotation thereon, the button having an exposed roughened head to engage a circuit breaker in a suitable fuse socket.

6. A plug fuse having a projecting boss of insulating material and a metal contact button mounted on said boss and secured against rotation thereon, the button having an exposed roughened head to engage a circuit breaker in a suitable fuse socket and there being venting passages through the boss adjacent to the surface of said contact button.
